United States Patent Office.

WILLIAM A. MIDDLETON, OF HARRISBURG, PENNSYLVANIA.

Letters Patent No. 88,057, dated March 23, 1869; antedated March 12, 1869.

COMBINED COAT-HOOK AND LINE-HOLDER.

The Schedule referred to in these Letters Patent and making part of the same.

To all whom it may concern:

Be it known that I, WILLIAM A. MIDDLETON, of Harrisburg, in the county of Dauphin, and in the State of Pennsylvania, have invented certain new and useful Improvements in Combined Coat-Hook and Line-Holder; and do hereby declare that the following is a full, clear, and exact description thereof, reference being had to the accompanying drawings, and to the letters of reference marked thereon.

The nature of my invention consists in the construction and combination of a coat-hook with a lever, so arranged as to form a line-holder.

In order to enable others skilled in the art to make and use my invention, I will now proceed to describe its construction and operation.

In the annexed drawings, forming part of this specification—

A represents a metal plate, secured, by any suitable means, to a wall, B, or wherever it may be desired to apply it.

At the upper end of said plate extends an arm, C, the outer end of which is bent upward, so as to form a hook.

On this arm C, a lever, D, is pivoted, said lever being so constructed as to form a ring, a, at its upper

end, and having, at its lower end, two arms, b b, extending, one on each side thereof.

The ends of these arms are bent toward the rear, or provided with flanges, c c, which project on the sides of the plate A, near its bottom end.

A rope, or line, d, passed up between one of the arms b and the plate A, and then through the ring a, forward, will press these arms close to said place, thereby holding itself tightly in place.

I am aware that a coat-hook and line-holder combined is, of itself, not new.

Having thus fully described my invention,

What I claim as new, and desire to secure by Letters Patent, is—

The coat-hook C, in combination with the lever D, constructed as described, or its equivalent, and acting as a line-holder, substantially as and for the purposes herein set forth.

In testimony that I claim the foregoing, I have hereunto set my hand, this 1st day of June, 1868.

WILLIAM A. MIDDLETON.
